UNITED STATES PATENT OFFICE.

GEORGE D. SHEER, OF CLEVELAND, OHIO.

DESIGN FOR A FENCE-PANEL.

SPECIFICATION forming part of Design No. 30,372, dated March 21, 1899.

Application filed February 9, 1898. Serial No. 669,722. Term of patent 7 years.

To all whom it may concern:

Be it known that I, GEORGE D. SHEER, of Cleveland, Cuyahoga county, Ohio, have invented and produced a certain new and useful Design for a Fence-Panel, of which the following is a specification, reference being had to the accompanying drawings, forming part thereof.

In the drawings, Figure I is a side elevation of a fence-panel embodying my design, and Fig. II is a plan in section on line 11 11, Fig. 1.

The leading or characteristic feature of the design consists in a fence-panel provided with pickets cruciform in cross-section, which pickets alternate with each other, as shown

in the drawings—that is, of every two adjacent pickets one is set with its arms arranged diagonally of the line of fence-panel, while the other picket has its arms arranged longitudinally of or at right angles to the said line.

What I claim is—

The design for a fence-panel, substantially as shown and described.

Signed by me, at Cleveland, Ohio, this 3d day of February, 1898.

GEORGE D. SHEER.
